Primary Examiner—Nelson C. Holtje*Attorney, Agent, or Firm*—Willian Brinks Hofer Gilson & Lione[57] **CLAIM**

The ornamental design for a clock face, as shown and described.

DESCRIPTION

FIG. 1 is a front elevational view of a clock face showing my new design; and,

FIG. 2 is a front elevational view showing a modified form of my new design.

The clock face is of no appreciable thickness and the rear is flat, plain and unornamented.
